UNITED STATES PATENT OFFICE.

JOHN J. CONWAY, OF BRIDGEPORT, CONNECTICUT, ASSIGNOR TO THE ACME SHEAR COMPANY, A CORPORATION OF CONNECTICUT.

DESIGN FOR A TENSION-SPRING FOR SCISSORS AND SHEARS, OR SIMILAR ARTICLE.

58,460.

Specification for Design.

Patented July 26, 1921.

Application filed April 18, 1921. Serial No. 462,454. Term of patent 14 years.

To all whom it may concern:

Be it known that I, JOHN J. CONWAY, a citizen of the United States, residing at Bridgeport, county of Fairfield, State of Connecticut, have invented a new, original, and ornamental Design for a Tension-Spring for Scissors and Shears or Similar Articles, of which the following is a specification, reference being had to the accompanying drawing, forming part thereof.

In the drawing Figure 1 is an elevation of a tension spring, embodying my novel design; and

Fig. 2 is an edge view thereof.

What I claim is:

The ornamental design for a tension spring for scissors and shears, or similar article, substantially as shown.

In testimony whereof I affix my signature.

JOHN J. CONWAY.
